BOTTLE

Leopold J. Hexel, Detroit, Mich.

Application May 15, 1953, Serial No. 25,027

Term of patent 14 years

(Cl. D58—8)

To all whom it may concern:

Be it known that I, Leopold J. Hexel, a citizen of the United States, residing in the city of Detroit, county of Wayne, and State of Michigan, have invented a new, original, and ornamental Design for a Bottle, of which the following is a specification, reference being had to the accompanying drawings, forming part thereof, in which:

Fig. 1 is a front elevational view of a bottle embodying my new design;

Fig. 2 is a side elevational view thereof; and
Fig. 3 is a top plan view thereof.

I claim:

The ornamental design for a bottle, substantially as shown.

LEOPOLD J. HEXEL.
